DESIGN FOR A DOLL

Benjamin Chalk, New York, N. Y.

Application November 2, 1945, Serial No. 123,412

Term of patent 7 years

(Cl. D34—4)

To all whom it may concern:

Be it known that I, Benjamin Chalk, a citizen of the United States of America, residing in New York city, county of New York, and State of New York, have invented a new, original, and ornamental Design for a Doll, of which the following is a specification, reference being had to the accompanying drawing, forming part thereof.

Fig. 1 is a front view of a doll showing my new design.

Fig. 2 is a front perspective view thereof.

Fig. 3 is a rear perspective view.

I claim:

The ornamental design for a doll, substantially as shown.

BENJAMIN CHALK.
